UNITED STATES PATENT OFFICE

131,199

DESIGN FOR A FLUORESCENT LAMP FIXTURE

Bernard A. Mitchell, Chicago, Ill.

Application December 4, 1941, Serial No. 104,458

Term of patent 7 years

To all whom it may concern:

Be it known that I, Bernard A. Mitchell, a citizen of the United States, residing at Chicago, in the county of Cook and State of Illinois, have invented a new, original, and ornamental Design for a Fluorescent Lamp Fixture, of which the following is a specification, reference being had to the accompanying drawing, forming part thereof.

The drawing is a perspective view of a fluo-

rescent lamp fixture showing my new design. The opposite end not shown is identical to the end shown.

The characteristic features of my design reside in the portion shown in full lines.

I claim:

The ornamental design for a fluorescent fixture, as shown and described.

BERNARD A. MITCHELL.
